NAILER SECTION

Walter L. Leedy, Youngstown, Ohio

Application April 26, 1948, Serial No. 23,287

3 Claims. (Cl. 189—37)

1

This invention relates to a nailer section usable as a structural element and in the formation of joists, studs and the like employed in building constructions.

The principal object of the invention is the provision of a nailer section usable as a structural element and capable of receiving and retaining various sizes of nails.

A further object of the invention is the provision of an improved nailer section having a bearing face for covering material comparable with that provided by corresponding wooden structural members and provided with means for receiving nails or other fastening means in transversely spaced areas thereof as for securing the covering material thereto; for example: the adjacent ends of the different members forming the covering member may be individually supported upon and effectively secured to the nailer section disclosed herein.

A still further object of the invention is the provision of a nailer section so constructed that its parts may be readily and economically secured together.

A still further object of the invention is the provision of a nailer section formed of metal parts so arranged and constructed that the nailer section is of relatively light weight.

The nailer section disclosed herein may be used in its basic form as applied to structural members to form appropriate nailer sections thereon or it may be formed into joists, for example, by utilizing oppositely disposed pairs of the nailer sections to form chords secured together by appropriate web members.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a perspective view of a portion of the nailer section.

Figure 2 is a cross sectional elevation taken on line 2—2 of Figure 1.

Figure 3 is a cross sectional view of the nailer section showing covering material applied thereto and nails secured therein.

By referring to the drawings and Figures 1 and 2 in particular it will be seen that the nailer sec-

2

tion comprises a pair of metallic channels 10 and 11, respectively, of different widths and assembled with the metallic channel 11 lying within the metallic channel 10 and in inverted relation with respect thereto. The metallic channel 10 is provided with longitudinally extending flanges 12 and 13 and the longitudinally extending center section of the metallic channel 10 is formed in a continuously extending ridge 14, the exterior or bottom of the metallic channel 10 thereby defining a continuously formed longitudinally extended, shallow V-shaped groove 15. The metallic channel 10 is formed with oppositely disposed curving side walls 16 and 17, respectively, which are formed on a relatively large radius adjacent the flange 13 and on a relatively smaller radius adjacent the longitudinally extending ridge 14. For example, in the disclosed form of the invention the relatively larger radii are formed as one inch radii whereas the relatively smaller radii are formed as one-half inch radii.

Still referring to Figures 1 and 2 of the drawings it will be seen that the metallic channel 11 is positioned within the metallic channel 10 in spaced relation with respect thereto and secured thereto by means of a plurality of tack welds 18—18. The metallic channel 11 is formed with inwardly converging side walls 19 and 20, respectively, and are formed on radii matching the radii of the walls 16 and 17 of the metallic channel 10. At the points of junction between the inwardly converging side walls 19 and 20 and the transversely flat section of the metallic channel 11 relatively small radii are formed to provide, in effect, oppositely disposed rolled edges 21 and 22 which are spaced relatively closer to the uppermost portions of the side walls 16 and 17 of the metallic channel 10 than the remainder of the side walls 19 and 20 of the metallic channel 11. It will be obvious to those skilled in the art that both the metallic channels 10 and 11 may be formed by rolling strip stock in a manner known in the art whereby the desired contours of the metallic channels may be formed.

It will be seen that when the metallic channel 11 is disposed within the area defined by the metallic channel 10, the transversely flat portion thereof will be in surface alignment with the longitudinally extending flanges 12 and 13 of the metallic channel 10 and thus present a suitable bearing surface upon which covering material may be placed as shown in Figure 3 of the drawings wherein two abutting sections of covering material 23 and 24 are illustrated.

By referring to Figures 2 and 3 of the drawings it will be seen that the spacing of the metallic channel 11 with respect to the metallic channel 10 forms a pair of longitudinally extending, spaced, nail securing slots 25 and 26, the width of the slots 25 and 26 varying between the members, as heretofore described, and the curvature of the slots varying, as heretofore described, in connection with the radii upon which the side walls of the metallic channels 10 and 11 are formed.

By referring to Figure 3 of the drawings it will be seen that when a nail 27 is driven through the covering material 24 so as to engage the slot 26, it will move vertically into the slot 26 for a relatively short distance and then follow the gently sloping, inwardly converging side walls 17 and 20, respectively, of the channels 10 and 11 with a small deflection from vertical. As the nail 27 is driven further into the slot 26 it will follow the relatively smaller radius defined by the lowermost portions of the side walls 17 and 20, as heretofore described, and thereby be caused to curve abruptly and assume a partial U-shape, as shown, by the completely driven nail 28 in the left hand section of the nailer section illustrated in Figure 3 of the drawings.

The nailer section shown and described herein may be used for receiving and retaining 10, 16 or 20 penny or common nails, the spacing of the side walls 19 and 20 of the metallic channel 11 being determined by the size of nail driven therein as the same are yieldably arranged in depending position with respect to the transversely flat section of the metallic channel 11. When the relatively larger nails are driven they will of necessity groove the rolled edges 21 and 22 as they are forcibly moved into the slots 25 or 26 thus providing an initial relatively high frictional engagement between the nailer section and the nail which compares with the action of a nail being driven into a compressible or distortable material and which action differs considerably with respect to the action of nailer sections as heretofore known in the art, particularly in the initial stages of driving the fastener thereinto.

It will be observed that as the nails are driven further into the slots 25 or 26 the first deflection from vertical is a relatively minor one and is easily imparted to the nail as it has previously created a vertical channel in the lower edges 21 or 22, which action prevents the nail from moving sidewardly out of its normal vertical plane, which action would interfere with driving the same into the nailer section. It is only after the nail has been first frictionally engaged and secondly distorted in limited degree that it enters the relatively smaller radius defined between the walls 20 and 17, for example, where it is imparted a final curve which effectively clinches the nail in the nailer section, as best shown in Figure 3 of the drawings.

In order that the nailer section may operate effectively it is necessary that the metallic channel 11 be formed of a relatively lighter gauge metal than that of the metallic channel 10. For example, in the embodiment of the invention disclosed with the radii as hereinbefore given and adapted for use with the nail sizes hereinbefore given, the metallic channel 11 should be formed of 14 gauge steel and the metallic channel 10 should be formed of 12 gauge steel. The criticality of the gauge of the metal used in forming the nailer section lies in the spring like tensioning action of the inwardly converging walls 19 and 20 of the metallic channel 11 with respect to a nail being

driven into the slots 25 or 26, particularly when nails of different sizes are employed.

It will thus be seen that a nailer section has been disclosed which incorporates several advantages over comparable structures heretofore known in the art in that primarily a driving action is obtained which closely resembles the driving action of a nail with respect to a wooden structural member in that the nail is initially frictionally held and then during its driving action. In the present invention it will be obvious that the initial holding action and guiding action contributes substantially to the successful clinching action which follows. It will be obvious to those skilled in the art that opposed pairs of the nailer sections herein disclosed may be joined in suitable web members for the formation of joists, studs and other structural elements or that the nailer section may be applied directly to existing structural shapes as desired.

Having thus described my invention, what I claim is:

1. A structural member comprising a pair of channel members one of which is upright and the other of which is inverted, the said upright channel member being wider than the inverted channel member and the inverted channel member being positioned in the area defined by the upright channel member and secured thereto at spaced intervals therealong with the web portions of the said channel members in oppositely disposed spaced relation to one another, the said inverted channel member having a transversely flat web portion, the upright channel member having longitudinally extending outturned flanges formed on the edges thereof, the surfaces of which are aligned with the said flat web portion of the said inverted channel member to form a flat top on the structural member, the web portion of the upright channel member formed in adjacently positioned longitudinally extending shallow U-shaped troughs and the side portions of the inverted channel member being transversely inclined toward one another to define longitudinally extending curved slots between the said channel members for the reception of fasteners.

2. A structural member comprising a pair of channel members one of which is upright and the other of which is inverted, the said upright channel member being wider than the inverted channel member and the inverted channel member being positioned in the area defined by the upright channel member and secured thereto at spaced intervals therealong with the web portions of the said channel members in oppositely disposed spaced relation to one another, the said inverted channel member having a transversely flat web portion, the upright channel member having longitudinally extending outturned flanges formed on the edges thereof, the surfaces of which are aligned with the said flat web portion of the said inverted channel member to form a flat top on the structural member, the web and side portions of the upright channel member formed in parallel longitudinally extending U-shaped troughs, the side portions of the inverted channel member being transversely inclined toward one another to define longitudinally extending curved slots between the said channel members for the reception of fasteners.

3. A structural member comprising a pair of channel members one of which is upright and the other of which is inverted, the said upright channel member being wider than the inverted channel member and the inverted channel member

being positioned in the area defined by the upright channel member and secured thereto at spaced intervals therealong with the web portions of the said channel members in oppositely disposed spaced relation to one another, the said inverted channel member having a transversely flat web portion, the upright channel member having longitudinally extending outturned flanges formed on the edges thereof, the surfaces of which are aligned with the said flat web portion of the said inverted channel member to form a flat top on the structural member, the web and side portions of the upright channel member formed in parallel longitudinally extending U-shaped troughs, the side portions of the inverted channel member being transversely inclined toward one another to define longitudinally extending curved slots between the said channel members for the reception of fasteners, the innermost ends of the side portions of the inverted channel member

5

being slightly upturned and terminating adjacent the longitudinal center line of the web portion of the said upright channel whereby the said longitudinally extending curved slots between the said channel members are of J-shape in transverse section.
